UNITED STATES PATENT OFFICE.

JOSEPH ZUBATY, OF FLINT, MICHIGAN, ASSIGNOR TO A C SPARK PLUG COMPANY, OF FLINT, MICHIGAN, A COMPANY OF MICHIGAN.

ILLUMINATED PANEL.

Application filed June 20, 1927. Serial No. 200,277.

This invention relates to instrument panels of the type mounted on the dashboard of an automobile, and constructed to carry the various instruments usually mounted 5 thereon.

The object of the invention is to provide an instrument panel which is simple in construction and composed of but few parts. A further object is to provide a single metal 10 plate carrying the instruments desired and also a light bulb for illuminating the dials. A further object is to provide an apertured, hinged cover plate for the instrument carrying plate, this cover requiring no glass and 15 having the double function of allowing both observation of and access to the instruments and also of reflecting light down to the floor of the machine and the parts thereon, instrument apertures in said plate being 20 shown as larger than corresponding apertures in said cover and the direction and extent of the mentioned reflection being adjustably variable by changing the inclination of said door.

25 Further objects and advantages of the invention will appear in the course of the following description, taken in connection with the accompanying drawings, and will be particularly pointed out in the appended claims.

30 In the drawings:

Fig. 1 is a front view of my improved instrument panel showing a portion of the dashboard broken away and showing the arrangement of the dials, and the location 35 of the hinge and fastening device;

Fig. 2 is a section on the line 2—2 of Fig. 1, with part of the speedometer head broken away, and showing the shape of the rear plate, the mounting of the light bulb and speedometer head, and the latch device for 40 holding the cover plate in fixed position. The cover plate is shown in a nearly closed position in full lines and in raised position in dotted lines.

45 The numeral 2 indicates generally the instrument panel or assembly comprised in or carried by an instrument board 1 which may be the dashboard of an automotive vehicle.

The panel or assembly comprises an apertured base plate 3 which may be fixed to the dashboard at a main opening therein in any ordinary way, as by screws or bolts, not shown; or, as shown, the base plate and the dash may be made from a single metal sheet, 50 stamped in the desired form to provide a

depressed portion for mounting the various instruments. The instruments are shown as all mounted from the front side to facilitate forward removal upon the lifting of a hinged and apertured cover plate. The 60 numeral 5 indicates a speedometer head which may be connected to the base by any ordinary means, as by small screws, not shown. The numeral 6 indicates a plate or flange carrying the light socket 7. The base 65 3 is shown as provided at this point with a special depression deep enough so that the light bulb 9, in the socket 7, is secured slightly in front of the front of the speedometer head 5. In the usual construction, a 70 strip is cut out of the side of each instrument toward the light and the resultant opening is covered with a transparent sheet, but I may avoid the necessity of this by applying white paint to the depression in which the light 75 bulb is set and to the under side of the hinged and apertured cover plate,—so that the instruments, protected by the mentioned cover and by their separate glass front plates, are indirectly illuminated to any de- 80 sirous desired degree by reflection from “standing” portions of said cover, the reflected light entering through said separate glass plates. The exact number of instruments and the order in which they are ar- 85 ranged is immaterial.

Hinged to the base member 3, as at 12, is the cover plate 13. This cover plate has openings as indicated in Fig. 1, corresponding to the location of the dials, the opening 90 over the speedometer head being indicated at 14. To vary the inward illumination of instruments, as well as the outward illumination, the cover plate is held in any ad- justed position by means such as any simple 95 adjustable latch. The device I have shown comprises a latch member 16 having notches 17 in its under side for fitting over the edge of the base in the slot 23. The latch mem- ber is held in place against the base by means 100 of the leaf spring 19 and is held on the cover plate by means of the coil spring 20 between the cover plate and the pin or abutment 21 on the latch member. The springs are made strong enough so that the latch is held firmly 105 in place, yet may be readily operated by means of the latch head 18.

If desired, the cover may be held in closed position against the base 3. If it is desired to illuminate the floor of the car, the cover 110

may be raised to any desired extent, for instance to the extent indicated in full lines in Fig. 2. In this position, the cover plate will reflect the light from the bulb 9 not only to the instruments but to the floor of the machine. If the operator desires access to the various instruments, he may lift the cover to an extreme position such as that shown in dotted lines in Fig. 2. Then the light bulb may be removed for replacement or any instrument removed through the front of the base plate. As may be readily discerned from the disclosure, the feature of having a hinged cover plate is not at all limited in its utility to an instrument panel illuminated as described, but on the contrary may be used with advantage in a panel in which the dials are illuminated by light which is enabled to enter each instrument by means of a slot covered with a transparent strip as described above.

What I claim is:

1. In combination, an instrument board formed with an opening, a base carrying one or more instruments and fixed to the instrument board at the opening, and a cover provided with separate apertures opposite said instruments and so secured as to permit both observation of and access to the instruments without removal of the base or said cover.
2. In combination, an instrument board formed with an opening, a base carrying one or more instruments and fixed to the instrument board at the opening, and means comprising an apertured and hinged cover plate permitting both observation and forward removal of the instruments without removal of the panel for the base.
3. In a device of the class described, an instrument board formed with an opening, a base carrying one or more instruments so mounted thereon as to be removable from the front side and fixed to the instrument board at the opening, and an apertured hinged cover for said base, the apertures therein being opposite said instruments and said instruments being forwardly removable upon a swinging of said cover.
4. In a device of the class described, an instrument board formed with an opening, an instrument carrying plate at said opening, lighting means depressed relatively to said plate, and an apertured cover hinged to swing upward adjustably to vary the illumination effected by said lighting means.
5. In a device of the class described, an instrument board formed with an opening,

an instrument carrying plate at the opening, lighting means in a special depression within said plate, said plate being provided with an apertured cover, hinged to swing upward, and means for adjustably retaining said cover in any one of a plurality of positions, to vary the effect of said lighting means.

6. In a device of the class described, an instrument board formed with an opening, a base plate carrying instruments, a source of light in a special depression within the base plate and in advance of the instruments, an apertured cover hinged to swing upward and provided with reflecting means, and means for adjusting said cover to a plurality of positions to vary the effect of said lighting means.

7. In a device of the class described, an instrument board formed with an opening, an apertured plate carrying instruments removable from the front side, an apertured cover hinged to swing upward, and means for adjusting said cover to a plurality of positions, including an extreme position which is favorable to the removal of instruments without removal of said plate.

8. In a device of the class described, an instrument board formed with an opening, an instrument plate at said opening having an instrument fixed thereon, a lighting element, a light reflecting apertured cover hinged to swing upward, and means for adjusting said cover to vary the lighting effect from said lighting element.

9. In an instrument panel, a base carrying one or more instruments and a bulb for illuminating said instruments, a plate provided with apertures through which said instruments are visible and pivoted to said base for swinging upward, and an adjustable connection between said cover plate and base and adapted to hold said cover plate alternatively in any one of a plurality of positions to obtain various illumination effects.

10. In a device of the class described, an instrument board formed with an opening, a base carrying an instrument and a lighting element, said lighting element being so positioned as to illuminate the face of said instrument by reflection, and an adjustable apertured cover for said base having an inner light reflecting surface adapted variably to reflect the light inward to said instrument and outward through said opening.

In testimony whereof I affix my signature.

JOSEPH ZUBATY.
